SAFETY RAZOR

Edward J. Gray, New York, N. Y.; Irene Carol
Gray executrix of said Edward J. Gray, deceased

Application November 13, 1945, Serial No. 628,081

22 Claims. (Cl. 30—67)

1

It is among the objects of the invention to provide a safety razor and blade combination, the elements of which are simple, rugged and inexpensive in construction, dispensing with the hinged or other movable blade clamping cap, and admitting for the fabrication thereof, of the use of known razor manufacturing equipment with but minor modifications therein, which razor permits expeditious mounting of the blade unit thereon without danger of injuring its cutting edge, with inherent retention of the blade, however thin and flexible, to assure the desired stiffness at the cutting edge thereof and with adequate drainage facilities, in which the cutting edge of the blade is inherently guarded when apart from the razor, thereby to preclude injury to the user or to the towel in handling and moreover to simplify both the original packaging and the ultimate disposal of the used blade.

In the accompanying drawings in which is shown one of various possible embodiments of the several features of the invention,

Fig. 1 is a perspective view showing the safety razor with the blade unit in position thereon,

Fig. 2 is a view in transverse cross section, showing the blade in the process of being applied or removed,

Fig. 3 is a view similar to Fig. 2 showing the blade unit in mounted position, and on line 3—3 of Fig. 1,

Fig. 4 is a dropped perspective view of the two elements making up the head,

Fig. 5 is a perspective view of the blade unit,

Fig. 6 is a plan view of the blade guard blank, and

Fig. 7 is a detail view of a modification, shown in section, similar to Fig. 3.

Referring now to the drawings, the blade unit comprises a generally rectangular blade 10 which may be and preferably is a segment of a Gillette wafer type blade, either of ordinary or ultra-high spring steel stock, of half or less than half the width of the double edge wafer, to present a rear non-cutting edge 11 and a front cutting edge 12.

According to the invention, the cutting edge of the blade is guarded, desirably by assembling therewith a U-shaped bail 13, which extends along and clears the lateral edges 14 as well as the cutting edge 12 of the blade and normally lies in the plane thereof and frames the same. Preferably the guard has a part integral therewith by which it is clamped to the blade, and which also performs the cutting-edge-clamping function of the razor cap that in various commercial forms of safety razor is commonly superposed over the blade.

2

In a preferred specific construction, the blade guard comprises a unitary blank of sheet metal desirably of resilient metal which may be non-ferrous if desired, such as hardened brass, generally rectangular in form as shown in Fig. 6, and symmetrical with respect to its median fold axis *a—a*. The guard blank folded on said median line *a—a* embraces the blade 10 and, as shown, is of length and width as thus folded, 10 which is greater than the corresponding dimensions of the blade, the corners of the guard bail near the ends of the cutting edge 12 being desirably rounded as at 15. The two leaves of the guard blank have a U-shaped slot therein, the 15 base 18 of which slot exposes the entire length of the cutting edge 12 including the ground or sharpened area thereof, and the legs 19 of the U-shaped slot expose the area adjacent the major length of the lateral edges 14 of the blade. Thus 20 the unitary blade clamping guard has blade clamp leaves 16 and 17 superposed over preferably all of the blade area except the cutting edge and the lateral margins and from the ends of the folded edge *a—a* beyond the lateral edges of the 25 blade, the U-shaped guard bail 13 extends along the lateral edges and the cutting edge of the blade and substantially in the plane thereof, that is, the sharp cutting edge 12 is substantially in the plane of engagement between the superposed U-shaped 30 bail portions 13 that are integral with the two clamp leaves 16 and 17 of the guard blank.

The doubled over leaves of the guard are in direct clamping engagement with each other as at 20 adjacent the fold edge *a—a* for a width rearwardly of the rear edge 11 of the blade 10. Desirably the guard has a median shallow notch 21 therein at its rear edge for positioning the blade unit in manner more fully described hereinafter.

40 Both blade clamping leaves of the guard are desirably stiffened adjacent the cutting edge 12. Such stiffening is effected by ribs, preferably embossments along and adjacent to the free longitudinal edges 22 of the clamp leaves. Preferably 45 the embossments are ribs or ridges 23 extending convexly outward at a narrow area between the edge 22 and the main area of the blade clamp leaves 16, 17.

A safety razor head construction of my invention that has a specific and particularly intimate coaction with the guarded safety blade just described and is particularly and uniquely designed for use therewith, will now be described. This razor desirably has a handle 24 and a hoe-type head 25 extending at right angles thereto. That head is desirably formed with means for clasp-

ing the blade unit, such clasp means being both at the forward and the rear edges of the head, and at least one of said clasp means being preferably resilient. The blade unit is thus resiliently and removably held on the head by clasping said unit between the forward and rear edges thereof. The clasp means are so positioned relative to the razor head that the guarded blade when in place thereon is anchored at its bail, with the cutting edge of the blade extending thereabove. Preferably the face of the head has an upstanding ridge formation 26, desirably interrupted as three or more segments near its front edge, to be straddled by bail 13, so that when the guarded blade is in place on the razor, the cutting edge 12 and the adjacent clamp leaves 16, 17 are deflected by such ridge formation upwardly out of the plane of the guard bail 13 for shaving.

In a specific and preferred construction shown, the head is composed of a molded, forged or cast block 28, the face of the latter preferably sloping downward from its rear to its forward edge, and a sheet metal holder or base 27 therefor. The base and the block are combined into a subassembly, the blade-clasping members being unitary parts of the base. For this purpose, the base may comprise a stamping, desirably of spring brass, upon which rests the underface of the block, the block having two lateral lugs 29 unitary therewith, protruding forward from the front edge thereof and desirably also a central lug 30 midway therebetween. The front of the base has blade-retaining means, desirably an upwardly bent flange 31 hooked over lugs 29 and 30 and bridging therebetween along the block. The upper edge of flange 31 desirably is inclined inward somewhat at 31' as shown, above the upper faces of said lugs 29, 30. The length of flange 31 between the lugs 29 and 30 is desirably spaced from the main area of the base by longitudinal slots 32, as shown. The rear edge of the base 27 has an upstanding tongue or leaf 33, desirably bent upward and inward to an acute angle with its lateral edges lodged in a shallow notch 34 in the rear edge of the block, and with its upwardly protruding resilient end formed with a blade-engaging transverse shoulder 33' preferably pressed therein. Thus the base with its blade-hooking flange 31 and its blade-clasping leaf 33 is preassembled as a unit with the block to make up the razor head. Laterally of the leaf 33, the rear of the block is desirably hollowed out to provide finger notches 35.

The handle 24 desirably has an upstanding screw stud 36 passing through a central aperture 37 in the base of the head and threaded into a corresponding socket 38 in the block 28.

For use, the guarded blade is positioned, as best shown in Fig. 3, with its guard bail 13 resting on lugs 29 and 30 of the block and against the blade-hooking flange 31 of the head. The rear edge of the blade unit is now pressed downward over the resilient forwardly convex holding leaf 33 which centers the blade unit by registering in notch 21. In this depression, the ridge 26 on the face of the head engages the longitudinal rib 23 of the lower blade clamp leaf 16, and as the blade is pressed downward at its rear edge against the head, the cutting edge 12 of the resilient blade 10, with its resilient guard clamp leaves 16, 17, is held up out of the plane of the guard bail 13 in shaving position. The clasping pressure is thus exerted across the width of the guard unit and not on the cutting element 10.

The cutting edge 12 is, however, stiffened in its deflected position against deflection from a straight line, by the stiffening ribs 23 of the clamp leaves that embrace the blade near its cutting edge 12. The width of the blade-hooking flange 31 held against the leaf determines the angle of incidence of the blade in shaving. The wide open space between the cutting edge 12, the guard bail 13 and the slots 32, longitudinally through the base 27 adjacent the blade-hooking flange 31, precludes clogging and affords ample clearance for drainage.

To remove the blade, the index finger is held under the blade unit at one of the finger notches 35 and the holding leaf 33 is pushed outward with the thumb. As soon as the rear of the blade has thus been unclasped, the blade unit, by virtue of the resiliency of the blade and of its clamp leaves, immediately resumes normal or undeflected position in which the cutting edge 12 lies within the guard bail 13. When the blade is then removed and handled, there is no danger of injury to the user or to the towel in drying.

It will be understood that the leaf 33 may be provided with a series of transverse shoulders 39, in any of which the rear edge of the blade unit may be clasped for adjusting to a more acute shaving angle than the usual angle determined by pressing the blade unit all the way down against the face of the shaving head, as shown in Fig. 7.

The blade head is of the utmost simplicity in that it involves but a single unitary head piece with no removable or hinged cap piece. What commonly serves as the blade cap is in effect the guard clamp 16, 17 which is part of the blade unit. The combined blade and guard unit is of little if any greater cost for materials and labor than is the familiar Gem type blade with its back of edge piece. While the guard piece requires more metal than the Gem type edge piece, the more costly blade element requires less metal. The guard is clamped about the blade with as great facility as is the edge piece of the Gem type blade, and in fact but little modification in the manufacturing equipment for assembling the Gem type blade, is required to render it suitable for assembling the blade unit of the present invention.

The blade unit of the present invention is applied to the razor head and removed therefrom with greater facility than in conventional razors, because it is simply laid down against the forward hooked flange 31 and pressed toward the head. There is no need for applying a removable cap piece and turning a handle to tighten it, or of opening or closing a hinged cap piece.

Since the cutting edge 12 of the blade unit is so well shielded by the guard 13 that it is substantially proof against injury to the user as above pointed out, the blade need not be wrapped in the original package but may be enclosed unwrapped in a suitably slotted box. Moreover the danger of dulling the cutting edge in the process of wrapper removal is completely obviated. Furthermore, the guarded blade of the present invention completely solves the troublesome problem of blade disposal, as the used blades can be safely thrown into a waste basket.

As many changes could be made in the above construction and many apparently widely different embodiments of this invention could be made without departing from the scope of the claims, it is intended that all matter contained in the 75 above description or shown in the accompanying

drawings, shall be interpreted as illustrative and not in a limiting sense.

Having thus described my invention what I claim as new and desire to secure by Letters Patent of the United States is:

1. A safety razor comprising a handle, a head, a blade and guard unit comprising a resilient blade having a cutting edge and an edge guard unitary with said blade and lying in the same plane as said cutting edge, means rising respectively from near the front and the rear edge of said head for releasably gripping the longitudinal edges of said blade guard, and a ridge conformation on the face of said head maintaining the cutting edge of the blade deflected out of the plane of the edge guard.

2. A safety razor comprising a handle, a head, a blade and guard unit comprising a resilient blade having a cutting edge, and an edge guard unitary with said blade and lying in the same plane as said cutting edge, said edge guard having integral therewith registering blade clamp leaves, at least one of said leaves having a stiffening rib longitudinally and near the edge thereof closest to the cutting edge, means rising from said head near the forward and the rear edges of the latter for releasably gripping the corresponding edges of the blade guard, at least one of said means being resilient, and a ridge conformation on the face of said head engaging the lower of the clamp leaves and deflecting the clamp leaves with the interposed cutting edge out of the plane of the edge guard.

3. A safety razor comprising a handle, a head, a blade and guard unit comprising a resilient blade having a cutting edge, an edge guard unitary with said blade and lying in the same plane as said cutting edges, comprising a bail framing the cutting and lateral edges of said blade, and a pair of clamp leaves integral with said bail and of resilient sheet metal clamping the face of the blade therebetween with the cutting edge exposed, said clamp leaves having stiffening embossments longitudinally thereof at the edge adjacent the cutting edge of the blade, blade and guard unit holding clasps rising from near the forward and rear edges of the head, one of said clasps being resilient, said clasps engaging the longitudinal edges of the blade and guard unit therebetween, and a ridge conformation rising from the face of the head near the forward edge thereof for maintaining the cutting edge of the blade and the associated clamp leaves deflected out of the plane of the edge guard.

4. A safety razor, comprising a handle, a head thereon, a spring metal blade having a cutting edge, a guard unitary with said blade and completely embracing the entire periphery of the blade and of width slightly less than that of the head, said head having coacting blade-retaining conformations to grip the longitudinal edges of said blade, at least one of said conformations being resilient, said head having means maintaining the cutting edge of the guarded blade deflected out of the plane of the guard.

5. A safety razor, comprising a handle, a head thereon, said head having blade-retaining means protruding upward from the forward edge thereof and having a blade-engaging resilient leaf spring protruding from the rear edge thereof, a blade unit comprising a blade with a cutting edge and a guard therefor, means releasably affixing said guard to said head, said guard completely encompassing the periphery of the blade and in the plane of the cutting edge thereof, said guard

being slightly less than the width of said head, said head having a conformation on its upper face, deflecting the cutting edge of the blade upward out of the plane of the guard.

5. A safety razor, comprising a handle, a head at right angles thereto having a blade mounting face with a forward inclination, a blade unit comprising a blade and a guard member therefor unitary therewith, said guard member having a portion affixed to the blade and a U-shaped bail framing the cutting and the lateral edges of said blade and substantially in the plane thereof, said guarded blade being slightly less than the width of the face of said head, clasp means at the forward edge of said head engaging said bail, resilient clasp means at the rear edge of said head engaging the rear edge of said guarded blade resiliently to mount the same in position, the face of said head having a ridge conformation deflecting the cutting edge of the blade out of the plane of the guard bail.

6. A safety razor, comprising a handle, a razor head comprising a sheet metal base and a block superposed thereover, said base having a flange having an inturned edge unitary therewith at the forward edge of said block, said base having a resilient upstanding leaf engaging the rear of the block, a blade unit comprising a blade having a cutting edge and a sheet metal guard therefor, embracing the back edge of the blade, overlapping a substantial area of the blade and having unitary with the ends thereof a U-shaped bail encompassing and framing the lateral edges and the cutting edge of the blade, said blade unit being of width equal to the width of said head with the inturned edge of said flange engaging the bail of the guard and the leaf resiliently engaging the rear edge of the guard, the block being conformed relative to the base to maintain the cutting edge of the blade deflected out of the plane of the guard bail.

7. The combination recited in claim 7, in which the handle has a screw stud extending through an aperture in the base and threaded into the block.

8. The combination recited in claim 7, in which the leaf fits in a corresponding groove in the rear edge of the block.

9. The combination recited in claim 7, in which the back of the guard has a notch accommodating the upper part of the leaf and registering the length of the guarded blade in respect to the head.

10. The combination recited in claim 7, in which the flange extends the length of the head and the head has lugs at its opposite ends engaging and holding said flange, and the sheet metal base presents a longitudinal slot extending between the lugs and spacing the base proper from the flange.

11. The combination recited in claim 7, in which the rear edge of the block has finger notches laterally of the leaf.

12. The combination recited in claim 7, in which the rear edge of the block has finger notches laterally of the leaf.

13. A safety razor head assembly, comprising a blade supporting block generally rectangular in plan with an outer face inclined forwardly, a sheet metal holder for said block comprising a plate on which said block rests, said plate having a hook conformation straddling the forward edge of the block and extending inward above the face of the block, said plate having an upstanding tongue unitary therewith gripping the rear edge of the block, said tongue having a resilient leaf extending above said block.

14. A safety razor head assembly, comprising

a blade supporting block generally rectangular in plan with an outer face inclined forwardly, a sheet metal holder for said block comprising a plate on which said block rests, said block having lugs protruding forward from the ends of the front edge thereof, said plate having a flange with an inturned edge embracing said lugs and bridging therebetween, said plate having an upstanding tongue unitary therewith, engaging the rear edge of the block, said tongue having a resilient leaf extension above said block, the base plate substantially conforming to the base area of the block and presenting a longitudinal slot separating the length of the hook conformation between the lug embracing ends thereof from the base proper.

15. A safety razor head assembly, comprising a blade supporting block generally rectangular in plan with an outer face inclined forwardly, a sheet metal plate on which said block rests, said plate having a flange with an inturned edge straddling the forward edge of the block and extending inward above the face of the block, said plate having an upstanding tongue unitary therewith engaging the rear edge of the block and having a protruding resilient leaf extension, the block having a groove at the rear edge thereof in which the tongue is lodged and having finger grooves laterally of the groove.

16. A guarded blade unit, comprising a cutting blade member and a sheet metal guard therefor, said guard having leaves clamping said blade along substantially the entire length of and including a U-shaped bail portion integral therewith framing the cutting and the lateral edges of the blade and normally substantially in the plane thereof.

17. A guarded safety razor blade unit, comprising a generally rectangular blade having a cutting edge and a sheet metal guard therefor comprising a substantially U-shaped piece of sheet metal encompassing said blade, said guard clamping said blade between the sides thereof, said guard including as an integral part thereof a U-shaped guard bail extending about and framing the cutting and the lateral edges of the blade and in substantially the plane thereof.

18. A guarded safety razor blade unit, comprising a generally rectangular blade with a cutting edge, a guard unitary therewith, said guard being of sheet metal and having two similar superposed leaves joined along one edge thereof, each of said leaves being of length and width greater than the length and width respectively of the blade, said leaves securely clamping the blade therebetween, said leaves presenting U-shaped slots along and exposing the entire length of the cutting edge and along and exposing substantial lengths of the lateral edges of the blade and defining a U-shaped guard bail ex-

tending about, framing said lateral and cutting edges and substantially in the plane thereof.

19. The combination recited in claim 18, in which the joined edge of the guard extends beyond the rear edge of the blade and said joined edge has a shallow median positioning notch therein.

20. A guarded safety razor blade unit, comprising a generally rectangular blade having a cutting edge, a guard unitary therewith, said guard comprising a generally rectangular substantially U-shaped sheet of metal having similar leaves which has a length and a width greater than the length and width respectively of the blade, the leaves of the guard having registering U-shaped slots therein exposing the entire length of the cutting edge and substantial portions of the contiguous lengths of the lateral blade edges, said leaves securely clamping the blade therebetween and having longitudinal stiffening conformations near the cutting edge of the blade.

21. The combination of a safety razor and blade comprising a handle, a head therefor, a blade having a cutting edge, a guard affixed to 25 the blade and presenting a bail portion substantially in the plane of the blade and extending about the cutting edge thereof, said guard having blade clamp leaves and having embossed stiffening ribs along those edges thereof adjacent 30 the cutting edge of the blade, said head having means clasping the forward and rear edges of said guard, the face of said head having an upstanding ridge conformation engaging and deflecting the cutting edge out of the plane of the 35 guard bail.

22. A safety razor comprising a head having clasp means protruding from the forward edge thereof and from the rear edge thereof for gripping the corresponding edges of a guarded blade 40 therebetween, said head having a ridge conformation near its forward edge for deflecting the guarded cutting edge to operative position, the rear clasp having a plurality of blade engaging teeth transversely thereof for selectively fixing 45 the cutting angle.
